Primary Examiner — Caron Veynar*Assistant Examiner* — Garth Rademaker(74) *Attorney, Agent, or Firm* — McCarter & English, LLP(57) **CLAIM**

The ornamental design for hole saw blade, as shown and described.

DESCRIPTION

FIG. 1 is a perspective view of a hole saw blade showing the present invention;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The broken lines in the figures show structure or boundaries that are not part of the claimed design.
